UNITED STATES PATENT OFFICE

113,532

DESIGN FOR A CURTAIN ROD WALL FLANGE

Jean O. Reinecke, Chicago, Ill., assignor to
Crane Co., Chicago, Ill., a corporation of Il-
linois

Application December 8, 1938, Serial No. 81,662

Term of patent 14 years

To all whom it may concern:

Be it known that I, Jean O. Reinecke, a citizen of the United States, residing at Chicago, in the county of Cook and State of Illinois, whose post-office address is 664 North Michigan Avenue, Chicago, Illinois, have invented a new, original, and ornamental Design for a Curtain Rod Wall Flange, of which the following is a specification, reference being had to the accompanying drawing, forming part thereof.

Fig. 1 is a front view of a curtain rod wall flange embodying my design.

Fig. 2 is a top plan view thereof.

Fig. 3 is a side view thereof.

I claim:

The ornamental design for a curtain rod wall flange, substantially as shown.

JEAN O. REINECKE.
